(57) **CLAIM**

The ornamental design for a barbecue tool hand grip, as shown and described.

DESCRIPTION

FIG. 1 is a front elevational view of a barbecue tool hand grip showing my new design;

FIG. 2 is a side elevational view thereof;

FIG. 3 is a top view thereof;

FIG. 4 is a bottom view thereof;

FIG. 5 is a front elevational view of a second embodiment;

FIG. 6 is a side view of the second embodiment;

FIG. 7 is a top view of the second embodiment;

FIG. 8 is a bottom view of the second embodiment;

FIG. 9 is a front elevational view of a third embodiment;

FIG. 10 is a side elevational view of the third embodiment;

FIG. 11 is a top view of the third embodiment; and,

FIG. 12 is a bottom view of the third embodiment.

The rear, bottom, side and end views not illustrated are mirror images of the front and side illustrated in FIG. 1 and FIGS. 5 and 6 and FIGS. 9 and 10 respectively, and the tool shank and rivets illustrated in dashed lines do not form part of the claimed design.
